SOUND PROPAGATING DEVICE

Application filed October 4, 1929. Serial No. 397,309.

This invention relates to sound propagating devices.

It is among the prime objects of the present invention to provide a novel and improved sound propagating device which is especially adapted for the faithful propagating of sound waves at an increased volume level.

A further object of the present invention is to provide a novel and improved cone sound propagating instrument including means for simultaneously actuating the cone surface at a plurality of points.

A further object of the present invention is to provide a novel and improved cone construction which includes reinforcing members associated with the cone surface for actuating the same.

Other objects of the present invention include the combination and interrelation of parts whereby the whole forms a novel, simple and improved structure adapted to provide a loud speaker which will faithfully reproduce sound waves at a high volume level.

Other objects and features of the present invention will be apparent from a consideration of the following specification taken in conjunction with the accompanying drawings, in which

Figure 1 is a vertical sectional view through one form of the present invention;

Fig. 2 is a sectional view taken on the lines 2-2 of Fig. 1;

Fig. 3 is a sectional view taken on the lines 3-3 of Fig. 1.

Referring more particularly to that form of the invention herein disclosed the device includes a conical surface 10, which may preferably be formed of paper or other suitable material and which is adapted to vibrate, thus to propagate sound waves in the conventional manner of a cone speaker. The surface 10 is adapted to be actuated from a coil 11, by means of an interconnecting driving tube or cylinder 12, the cone end of which is provided with return bent flanges 13, which engage the inner face of the surface 10 at the point indicated, which point will be seen to be symmetrically spaced from the apex of the surface. The tube may be cemented or other-

wise suitably joined with the surface whereby a joining equal to the circumference of the tube is provided. Associated with the driving tube 12, further means for delivering periodic rectilinear motion from the tube to the surface for vibrating the same is provided, which means includes a truncated cone 14 cemented or otherwise joined to the tube as at 15 and extending forwardly and outwardly therefrom to be joined with the surface as at 16. The joining of the surface with the truncated cone 14 is preferably similar to the joining of the tube with the cone, whereby a circumferential cement union is provided.

A further reinforcing and vibration imparting structure is provided in conjunction with the surface 10 and the cone 14, which includes a cylindrical member 17 concentrically spaced from the tube 11, its forward end being joined with the surface 10 at 16, with the forward end of the cone 14, while the rear end of the tube is joined by a member 18 preferably formed integral therewith, to the surface 10, as at 19. The member 18 is in the form of a second truncated cone concentric with the truncated cone 14, the arrangement being such that upon vibration of the coil 11, the tube 12 will be rectilinearly moved and will impart its vibration to the cone surface through the joints 13, 16 and 19, which by virtue of their interconnection, simultaneously actuate the cone at a plurality of circumferentially spaced points. The periphery of the cone surface is joined to a suitable flexible member 20, as at 21, the member 20 being secured upon a frame 22 by a suitable securing rim 23.

In some instances, particularly in the use of a large cone with a large driving tube 12, it may be preferable to provide a further reinforcing and vibration imparting structure within the driving tube, so that the apex of the cone will be caused to vibrate in unison with the surrounding surface. In such instances, the internal structure as here shown is utilized, which consists of a small internal tube 12^A joined to the cone concentrically thereof and near its apex as at 13^A. The rear end of the tube 12^A is connected to the tube 12 by a frusto-conical structure 14^A, the

structure 14^a being joined to the rear end of the tube 12^a, and the forward end of the tube 12, as at 15^a and 16^a, respectively. It will be seen that the internal structure is structurally equivalent to and functions as the other tubular members carried upon the truncated portions 14 or 18, whereby the whole vibrating surface of the cone will be caused to vibrate in unison as distinct from the vibrations of the apex of a cone which pass from the apex outwardly. It will be understood that the invention is not confined to the use of the internal structure but that the use of the structure is controlled by the characteristics of the cone.

For supporting the coil 11 and the associated free end of the tube 12 in the usual circular gap 24 of the electromagnet, actuating unit, generally indicated by the numeral 25, a plurality of supporting threads 26 are provided which are joined as at 27, to the tube 12, while their opposite ends are supported upon suitable fingers 28 associated with the unit 25. The arrangement is such that the desired tension may be placed upon the threads to support the coil accurately in the center of the air gap in such manner that the coil may not move radially but is free to move rectilinearly. It will be seen that the member 20 is also free to move with the tube. It will further be seen that the restoring force of the supports 26 and 27 in a direction parallel to the tube is so low that the natural period of the structure with the surface 10, is below any voice or musical frequency.

It is well known that in order to obtain high volume of sound reproduced from electrical impulses by means of a diaphragm, there must be a large area of projecting surface or its equivalent, and a fair degree of amplitude in the motion of the diaphragm. If amplitude of motion is increased to get high volume, considerable energy may be transferred to the air from a relatively small projecting surface, but the sound will be at a high pressure, which is undesirable. On the other hand, if the area of the projecting surface is increased, the diaphragm usually rattles, or vibrates locally, giving rise to noises, and the high frequency impulses travel from the source along the diaphragm in the form of progressing waves until the outer edge of the diaphragm is reached. The progressive travel of the higher frequencies from the source causes interference of sound projected from the diaphragm at different instances, as well as reduces the effective area of the projecting surface.

If the actuating force of the coil is applied only at a point near the vertex of the sound projecting surface, the impulse must travel along the projecting surface to the outer edge of the cone, thus creating considerable phase difference between the sound produced

at the point of application and at the edge of the cone for large diaphragms, and at the higher frequencies. If, however, the actuating force is applied to the sound projecting surface by means of suitable links to essentially all parts of the diaphragm, and the links are of the same material and have practically the same length to the projecting surface from the actuating coil, all impulses will reach essentially all points on the sound projecting surface simultaneously, thereby causing the sound projecting surface, which may be large, to move as a whole at all frequencies.

The multiplicity of points on the sound projecting surface also prevents rattle of the surface, or local vibrations that are more or less independent of the movement of the diaphragm as a whole when large diaphragms are used.

Another characteristic of the reenforced structure is that due to the shape of the sound projecting surface, there is practically no directional effect in the projection of sound at any frequency.

From the foregoing it will readily be seen that the invention provides a novel, simple and improved sound propagating device which is adapted to minimize the propagation of parasitic wave formations and to provide for faithful reproduction of sound waves. In connection with the invention, it will be understood that the device is not confined to the specific structural details herein enumerated but that numerous changes, modifications and the full use of equivalents may be resorted to without departing from the spirit or scope of the invention as outlined in the appended claims.

What is claimed is:

1. In a sound propagating apparatus, the combination with a sound propagating diaphragm, of an actuating unit associated therewith, said unit including a plurality of concentrically arranged tubular members engageable with said diaphragm.

2. In a sound propagating apparatus, the combination with a conical sound propagating diaphragm, of an actuating unit associated therewith, said unit including a plurality of concentrically arranged tubular members engageable with said diaphragm, each of said tubular members being in axial alignment with the axis of said diaphragm and contacting with the diaphragm over the entire circumference of one end thereof.

3. In a sound propagating device, the combination with a diaphragm, of actuating means therefor, including a tubular driving arm secured to said diaphragm, and a truncated conical member diverging from said arm and engageable with said diaphragm.

4. In a sound propagating device, the combination with a diaphragm, of actuating means therefor, including a tubular driving

arm secured to said diaphragm, and a truncated conical member diverging from said arm and engageable with said diaphragm in spaced relation to the engagement of said tubular arm.

5. In a sound propagating device, the combination with a diaphragm, of actuating means therefor, including a tubular driving arm secured to said diaphragm, and a truncated conical member diverging from said arm and engageable with said diaphragm in spaced relation to the engagement of said tubular arm and concentric therewith.

10. In a sound propagating device, the combination with a diaphragm, of actuating means therefor, including a tubular driving arm secured to said diaphragm, a truncated conical member diverging from said arm and engageable with said diaphragm in spaced relation to the engagement of said tubular arm and concentric therewith, a second tubular arm carried by said truncated member, and diaphragm-actuating means carried by said second arm.

15. In a sound propagating device, the combination with a diaphragm, of actuating means therefor, including a tubular driving arm secured to said diaphragm, a truncated conical member diverging from said arm and engageable with said diaphragm in spaced relation to the engagement of said tubular arm and concentric therewith, a second tubular arm carried by said truncated member, and diaphragm-actuating means carried by said second arm, said means including a second truncated conical member.

20. In a sound propagating apparatus, a conical diaphragm, and a plurality of concentrically arranged tubular engaging actuating means each of said tubular means engaging the diaphragm for the entire circumference of one end thereof.

25. In a sound propagating device, a conical diaphragm, and means for simultaneously actuating said diaphragm at a plurality of points, said means including a plurality of concentrically arranged tubular members associated with said diaphragm each of said tubular members engaging the diaphragm for the entire circumference of one end thereof.

30. In a sound propagating device, a conical diaphragm, and means for simultaneously actuating said diaphragm at a plurality of points, said means including a plurality of concentrically arranged tubular members associated with said diaphragm, an intermediate one of said tubular members extending rearwardly from said conical diaphragm for association with an actuating means.
